UNITED STATES PATENT OFFICE

EDWARD H. TAYLOR, EDGAR F. SEIFERT, AND CARL OTTOKAR MERICKA, OF CHICAGO,
WILLIAM M. LOSER, OF WHEATON, HARRY R. BEHNKE, OF VILLA PARK, AND
HOWARD SOMERVELL, OF EVANSTON, ILLINOIS, ASSIGNEES, BY MESNE ASSIGN-
MENTS, TO CONSOLIDATED SIGNAL COMPANY, A CORPORATION OF ILLINOIS

CROSSING GATE

Application filed August 20, 1930. Serial No. 476,578.

This invention pertains to crossing barriers, and more particularly to automatic and multiple safety gate and signal systems.

5 In safety barrier systems, the most satisfactory method of guarding a railway crossing, there are a number of problems which must be solved. First of all, an adequate crossing barrier must be provided which is positive in operation, affords adequate protection, and operates on the safety side, being preferably automatically controlled by track vehicles. Obviously, crossing barriers which are manually operated, even 10 though the first cost may be less than that of an automatically controlled barrier, are more expensive in the long run since an attendant must always be at the crossing to raise and lower the crossing gates at the 15 approach of a train, this attendant must be sheltered, and some means provided whereby the approach of the train is indicated to him. Another consideration is that the 20 crossing gate must be as inexpensive as possible, for at least two gates must be installed 25 at a crossing.

With the old type of gates, if a road vehicle is trapped between the lowered crossing gates, the road vehicle was either hit 30 by the approaching train or must break through the crossing gate, causing damage to either the gate or the vehicle, or both, so that it is desirable that there be some safety feature connected with the gate whereby 35 the gate can be rendered inoperative for a short period of time to take care of any emergency whereby a motorist is trapped between the gates when in lowered position, and this safety feature preferably should 40 not involve the raising and lowering of the gates, as this is slow and opens the crossing at the time when a train is approaching.

There are other contingencies which may 45 arise which should be taken care of for the crossing gate to be successful, one of which

is the condition wherein the gates may be lowered and strike, say, the upper portion of a road vehicle. This frequently occurs where the motorist approaches at too great a speed and so is not able to stop in time. 50

Other types of gates may be desirable, such as a gate which is not swingable in a horizontal direction, which type of gate would be especially adaptable for use as a sidewalk gate or over roads where only low 55 speed traffic is found. In conjunction with this type of gate it may be desirable to provide a construction wherein the operating mechanism is disposed wholly in the gate supporting head so that it may be adapted 60 to existing standards as well as those new supports used in the complete device.

With the above referred to types of gates a positive and effective switching mechanism must be provided and one which can 65 be readily rendered inoperative, yet one which is positive in operation and is simple to operate.

It is therefore an object of this invention to provide a barrier construction which, 70 while effective to provide safety means at a crossing, is still yieldable to impact and/or obstruction.

Another object of the invention is to provide a crossing barrier which, though positive in operation, is operable in a manner whereby jarring of the barrier and consequent overload of parts of the device is 75 prevented.

A further object of the invention is to 80 provide a crossing barrier system wherein a plurality of means of operation is provided, one of which is normally inoperative and is only operative upon failure of the normally operative means.

A yet further object of the invention is to 85 provide a crossing barrier wherein the operating means is disposed in the gate supporting head thereof whereby a compact and interchangeable unit is provided. 90

A still further object of the invention is to provide a switch mechanism which is operable to control the operating devices for raising and lowering the barrier arms.

5 Another further object of the invention is to provide a barrier and system of operation therefor which fulfills all requirements of manufacture and service.

10 With these and various other objects in view, the invention may consist of certain novel features of construction and operation, as will be more fully described and particularly pointed out in the specification, drawings and claims appended hereto.

15 In the drawings, which illustrate an embodiment of the device and wherein like reference characters are used to designate like parts—

20 Figure 1 is a vertical sectional elevation of one form of the device embodying the invention;

25 Figure 2 is a fragmentary side elevation of the device shown in Figure 1;

30 Figure 3 is an enlarged sectional elevation through the gate supporting head of the barrier shown in Figure 1;

35 Figure 4 is an enlarged fragmentary sectional elevation taken substantially at right angles to the head of the barrier shown in Figure 3 showing the gates in lowered position.

40 Figure 5 is a sectional elevation, corresponding to Figure 1, of a modified form of the device;

45 Figure 6 is an enlarged sectional elevation through the antifriction bearing assembly for the barrier shaft;

50 Figure 7 is an enlarged fragmentary sectional elevation of a part of the head of the construction shown in Figure 5, showing means for carrying electrical connections from the standard into said head;

55 Figure 8 is an enlarged sectional elevation of a modified form of means for carrying electrical connections into the head;

60 Figure 9 is a side elevation of the switch control mechanism adapted for use with the devices illustrated in Figures 1 to 5, inclusive;

65 Figure 10 is a side elevation taken at the opposite end of the switch control mechanism shown in Figure 9;

70 Figure 11 is a top plan view of the switch control mechanism shown in Figures 9 and 10; and

75 Figure 12 is an end elevation of the device looking toward the left, as viewed in Figure 9.

80 Referring first of all more particularly to the assembly of the barrier shown in Figures 1 to 4, inclusive, and 6, the standard or pedestal 20 is provided with the base 22 for supporting the pedestal casing 24, which casing is provided with suitable removable cover plates 26 and 28 permitting ingress

85 into the interior of the pedestal casing. The barrier supporting head 30 is preferably a casting provided with depending spaced rim flanges 32 adapted to embrace the rim flange 34 disposed on the pedestal casing and between which suitable packing 36 may be interposed to prevent the entrance of foreign matter into the casing. The head and casing are provided with securing lugs 38 and 40 to receive the securing means 42 which is shown in the form of bolts for fastening the head to the casing. The head is closed by means of the removable cap 44 bolted thereto as at 46 and provided with the embracing flanges 48 adapted to embrace the rim of the head between which insulating packing 50 is provided.

90 The head is preferably cast with recesses or aligned bosses 52 braced to the side of the casing by suitable gussets 54, said bosses being adapted to receive the roller bearing assemblies 56. These assemblies are inserted in the bosses 52 from the outside thereof, and consist essentially of an outer cup 58 adapted to be seated against the shoulder 60 formed in the boss and retained in position by means of the outer collar 62. The anti-friction rollers 64 are disposed between the cup and the cone 66 and mounted on the transverse shaft 70. The cone is maintained 95 in operative position on the shaft 70 by means of the shrink collar 72, and the space between the outer periphery of the boss and the shaft 70 is closed by means of the cover plate 74 secured to the casing as at 76. The shaft 70 extends outwardly of the head and is provided with the pinion 78 mounted thereon and having cooperative relation with the rack 80 mounted on the barrier arms 82. Lubrication of the antifriction 100 bearings may be had through a suitable aperture formed in the cover plate as at 75, or on the boss as at 77, the latter extending to the lubricant recess formed in the boss.

105 The barrier arms, shown provided with the adjustable counterweight 84, are adapted to operate between two positions limited by the transverse stops 86 secured to the casing 24, in the raised position, and by the transverse stops 88 secured to the bracket 90 on the head, in the down position. The rack 80 is contained in a suitable casing 92 disposed to open only inwardly of the barrier arms whereby grit and dirt are prevented from entering the casing and obstructing 115 operation of the rack and pinion.

120 The head is preferably cast with recesses or aligned bosses 52 braced to the side of the casing by suitable gussets 54, said bosses being adapted to receive the roller bearing assemblies 56. These assemblies are inserted in the bosses 52 from the outside thereof, and consist essentially of an outer cup 58 adapted to be seated against the shoulder 60 formed in the boss and retained in position 125 130

by means of the outer collar 62. The anti-friction rollers 64 are disposed between the cup and the cone 66 and mounted on the transverse shaft 70. The cone is maintained in operative position on the shaft 70 by means of the shrink collar 72, and the space between the outer periphery of the boss and the shaft 70 is closed by means of the cover plate 74 secured to the casing as at 76. The shaft 70 extends outwardly of the head and is provided with the pinion 78 mounted thereon and having cooperative relation with the rack 80 mounted on the barrier arms 82. Lubrication of the antifriction bearings may be had through a suitable aperture formed in the cover plate as at 75, or on the boss as at 77, the latter extending to the lubricant recess formed in the boss.

The barrier arms, shown provided with the adjustable counterweight 84, are adapted to operate between two positions limited by the transverse stops 86 secured to the casing 24, in the raised position, and by the transverse stops 88 secured to the bracket 90 on the head, in the down position. The rack 80 is contained in a suitable casing 92 disposed to open only inwardly of the barrier arms whereby grit and dirt are prevented from entering the casing and obstructing operation of the rack and pinion.

A support 94 is secured in the head casing to suitable brackets 96 preferably formed integral therewith, said support serving to provide securing means to which the motor units 98 and 100 of the direct and alternating current type may be fastened. The motors are provided with drive shafts 102 and 104 provided with pinions 106 and 108 adapted to mesh with the gear 110 fixed to the shaft 112 journaled in the gear housing 115, said gear housing being carried by the transverse supports 116. The shaft 112 is adapted to drive the vertical shaft 114 journaled in the casing as at 116 and 118 through the gear train 120—122.

The upper portion of the shaft 114 externally of the housing is provided with the worm 124 meshing with the gear 126 mounted on the shaft 70 whereby movement of the shaft 114 is imparted to the shaft 70. The lower end of the shaft 114 is provided with the universal joint 128 through which said shaft is connected to the drive shaft 130 connected through the universal joint 132 to the vertically extending shaft 134 of the control switch 136. The base 138 of the switch 136 is mounted on suitable brackets 140 provided in the casing 24, and suitable connecting bars 142 and 144 are secured to the casing 24 and the head 30 at convenient points therein for effecting the proper electrical connections, the conductors being preferably carried in the casings 146 and 148 disposed in the casing and head.

In the construction shown in Figure 5,

the barrier arms 82 are mounted on the transverse shaft 70 to be operated in a similar manner by the motors 98 or 100, said motors being adapted to drive the vertical shaft 114 journaled as at 116 and 118 in the casing 115. The drive to the shaft 114 is through the gear 110 and shaft 112 and gear train 120—122. In this instance, however, the vertical shaft 114 is provided with the gear 150 meshing with the gear 152 carried by the operating shaft 154 suitably journaled in bearings as at 156 in the head 30 and located in the center line of the mounting of the head on the casing 24. The casing 24 is provided with the closure plate 158 secured thereto as at 160, the inner depending flanges 162 of the closure plate embracing the vertical tube 164 forming a mounting for the head. The head is secured to the tube as at 166 and is provided with the depending skirt 168 embracing the cover plate 158 to prevent entrance of any foreign matter into the casing.

The tube forms a rotatable support for the head and is journaled into suitable bearings at 170, the bearing housing being carried on the platform 172 secured in the casing 24. The tube is provided with the gear segment 174 fixedly secured thereto and meshing with the gear segment 176 secured to the jack shaft 178 suitably journaled into the casing 24. The jack shaft 178 is provided with the yoke 180 rotatably mounted with respect thereto and being adapted to be engaged by the pins 182 carried on the gear segment 176. The depending arms of the yoke 180 are pivoted as at 184 to the depending rods 186 which extend through suitable apertures formed in the platform 172. The ends of the arms are provided with spring caps 188 and are each provided with the expansion springs 190 located between said caps and suitable caps or positioning means 192 provided on the platform 172.

It will thus be seen that movement of the head can be effected with respect to the standard, transverse movement of the barriers causing the head to rotate on the tube 164 and the bearings 170. This movement will cause the gear segment 172 to operate the gear segment 176 in a manner depending upon the rotation of the head 30. This movement will be imparted to the yoke by means of the proper pin 182, causing one of the springs 190 to be compressed between the spring caps, this compression causing return of the head to its normal position when the barrier arms are freed from obstruction. The movement will be permitted without change in the operating mechanism by virtue of the gear train 150—152 and the fact that the operating shaft 154 is located on the center line of the tube 164. The operating shaft 154 extends downward.

ly and is connected through the vertical shaft 134 of the control switch 136 which is mounted on the brackets 140 as before described.

5 As it may be desirable to provide electrical signals on the gate arm or head, and as an electrical connection must be made to operate the motors, the floor 31 of the head 30 is provided with a boss 151 disposed within 10 the boundary of the member 164. The individual conductors of the member 147 may be secured through a universal joint 153 to a sleeve 155, said sleeve having contact with a piston 157 and through a shoulder 159 with the piston rod 161. Between the shoulder and piston there is disposed a spring 163 to take up slack. The piston rod is secured through a universal joint 165 with the binding post 167 extending into 15 the head through the insulating sleeve 169, to which post is secured the proper conductor 149 running to the proper binding posts 144 (not shown in Figure 5).

In the modification shown in Figure 8, 25 the shaft 154 is provided with a supporting collar 171 forming a support for the arm 173 loosely mounted on said shaft. The arm 173 may be of insulating material, or 30 may be metallic carrying insulated brushes 175 spring pressed as at 183, to which are secured the conductors 147 of the member 148. The brushes have sliding electrical 35 contact with the contact rings 177 mounted on insulation 179 carried by said head, each contact ring being suitably connected to binding posts 181 to which conductors are secured to effect connection to the proper binding posts 144.

An alternative form may have a long flexible cable 148 extending directly into the head and having sufficient slack in member 164 to provide for at least a 90° oscillation of said head.

This invention, of course, contemplates 45 the use of a reversible motor, and to this end switch mechanism must be provided which will permit reversing of the operating shafts 130 or 154, depending upon which device is used. The switch 136 is mounted 50 on the base 138 which is provided with the bracket arms 194 on which is mounted the insulating switch bar 195 carrying spaced depending switch fingers 196 and 198, said switch fingers being adapted to be electrically connected to the source of supply and 55 the operating mechanism through suitable binding posts 200, each being connected to a finger. The shaft 134 journaled in the housing or base 138 is provided with the 60 reversible worm 202 adapted to have co-operative relation with the gear 204 mounted to drive the shaft 206 provided with the lifting pawl 208 adapted to engage the pin 210 provided on the switch arm 212, the end 65 of said switch arm being provided with the

insulating member 214 carrying the contact points 216 for establishing electrical connection between the respective spaced switch fingers 196 when in contact therewith.

70 The lifting pawl 208 is provided with the shoulder 218 for engaging the pin 210. As the switch mechanism described herein must be in duplicate to control up and down movements of the barrier arms and as reverse operation serves to control the switch arms, 75 the shoulder 218 on the opposing pawl is oppositely faced as shown in Figures 6 and 9 as opposite switch arms are operated by the shaft 206, the shaft operating said switch arms in reverse rotation. The switch arms are mounted on the shaft 220 suitably journaled in the base and provided with the upwardly extending locking members 222. The switch arm is provided with an outwardly extending portion 224 pivoted 80 as at 226 to the upwardly extending rod 228, the rod being provided with the spring cap 230 between which and the seat 232 is mounted the expansion spring 234, the seat 232 being conveniently mounted on the base 85 by means of the members 236.

Intermediate the pivots 220 and 226 there is provided the latching and trip pawl 238 pivoted thereto as at 240 and provided with the shoulder 242 disposed in way of the locking member 222, the member 238 being further provided with the forwardly extending arm or finger 244. The shaft 206 is further provided with the disk 246, said disk having the pin 248 provided thereon and extending in way of the finger 244 providing lifting means for the finger to release engagement between the shoulder 242 and the member 222. The disk is also provided with the pin 250 adapted to be restricted in its movement by the pin 252 mounted on the switch arm. 95 100 105

In operation of this switch member it will be understood that closing the contacts between switch fingers 196 serves to operate the motor in one direction, while closing the switch fingers 198 serves to operate the motor in reverse direction, and where a crossing gate assembly is used provided with both A. C. and D. C. motors, another 110 set of switch elements may be provided similar to the ones just described and operating parallel therewith. With such operation of the switch members it will be appreciated 115 that when one set of switch fingers is closed as shown in Figure 6, the other one is open as shown in Figure 9, and accordingly the operating pawls and the discs are angularly set one with respect to the other. 120

Assume the gates to be in raised position 125 and assuming that when the fingers 196 are closed, the motor will be operated to move the barrier arm to down position when current is supplied when a train enters the block closing the proper relays to supply current 130 135

to the motor through the switch fingers 196, the barrier moving to down position, causing rotation of the shaft 134. Rotation of the shaft 134 causes the worm 202 to operate the gear 204 to cause rotation of the shaft 206. Movement of the shaft 206 in a clockwise direction as viewed in Figure 6 causes the pin 248 to lift the arm 244 to release engagement between the member 222 and the shoulder 242, and this release will cause the spring 234 to snap the switch arm downwardly, breaking connection between the switch fingers and the contact pin 216; the downward limit of the switch arm being determined by engagement between the yoke shaped portion thereof and the shaft 206. While this operation is being effected rotation of the shaft 206 causes the member 208, as viewed in Figure 9, to raise the opposite switch arm 214 to establish connection between the switch fingers 196, and as the pin 248 is moved out of engagement with the portion 244 an interlock is caused between the shoulder 242 and the member 222, locking the switch arm in contact position compressing the spring 234. When the switch arm shown in Figure 6 has been moved to open position current is cut off from the motor causing the gate to remain in down position as the relay has not operated to direct current through the switch arms 196 while the train is in the block.

When the train leaves the block, of course, the relay will operate to supply current to the motor through the switch fingers 196 to operate the motor in a reverse direction to raise the gates. This operates the shaft 134 in reverse direction which in turn operates the shaft 206 in a counter-clockwise direction, as viewed in Figure 6, causing a reverse operation of the mechanism, that is, an opening of the connection between the switch fingers 198 and a closing of the switch fingers 196 whereby the mechanism is in condition for operation as just described upon entrance of a train in the block.

As the movement of the switch is slight to effect operation should a train enter the block after another train has left, but before the gate has reached its full up position, the switch will be in position whereby the gate will be immediately returned to down position, so that no time will be wasted in raising the gate to full up position first. This, of course, precludes the difficulty of leaving the crossing unprotected at any time.

It is to be understood that we do not wish to be limited by the exact embodiment of the device shown, which is merely by way of illustration and not limitation, as various and other forms of the device will of course be apparent to those skilled in the art without departing from the spirit of the invention or the scope of the claims.

We claim:

1. In a crossing gate, the combination of a supporting standard, a barrier arm supporting head having a member received in said standard for movably supporting said member and head, and means for maintaining said head in normal position and returning the same thereto after movement, said means including a pivotally supported member movable in accordance with the movement of said first named member, and means for returning said last named member into its normal position.

2. In a crossing gate, the combination of a supporting standard, a barrier arm supporting head having a member received in said standard, means associated with said standard for movably supporting said member and head, means for maintaining said head in normal position and returning the same thereto after movement, said means including a pivotally supported member movable in accordance with the movement of said first named member, and resilient means for returning said last named member into its normal position.

3. In a crossing gate, the combination of a supporting standard, a barrier arm supporting head having a member received in said standard, means associated with said standard for movably supporting said member and head, means for maintaining said head in normal position and returning the same thereto after movement, said means including a pivotally supported member movable in accordance with the movement of said first named member, and resilient means co-operating with said supporting means for returning said last named member into its normal position.

4. In a crossing gate, the combination of a supporting standard, a barrier arm supporting head having a member received in said standard, means associated with said standard for movably supporting said member and head, means for maintaining said head in normal position and returning the same thereto after movement, said means including a pivotally supported member movable in accordance with the movement of said first named member, rods depending from said last named member, and resilient means carried by said rods and cooperating with said supporting means for returning said last named member into its normal position.

5. In a crossing gate, the combination of a supporting standard, a barrier arm supporting head having a member received in said standard, means associated with said standard for movably supporting said member and head, means for maintaining said head in normal position and returning the same thereto after movement, said means includ-

ing a pivotally supported member movable in accordance with the movement of said first named member, rods depending from said last named member, guide means on said supporting means for said rods, and resilient means carried by said rods and cooperating with said supporting means for returning said last named member into its normal position.

10 Signed at Chicago, Illinois, this 4th day of August, 1930.
